BATTERY POST CLAMP

Harry R. Martin, Des Moines, Iowa

Application April 20, 1942, Serial No. 439,789

7 Claims. (Cl. 173—259)

1

This invention relates to battery connections and is more particularly concerned with a clamp or fastening means for securing a cable, adapted to transmit electric current, to a post of a wet storage battery.

Perhaps the most unpleasant, laborious and despised minor task encountered in the servicing of an automobile has heretofore been the removing of the battery terminal post connections, an operation necessary when interchanging batteries. The presently almost universally accepted clamp comprises a two jaw unit having a centrally located enlarged orifice for receiving the battery post. The extended ends of the jaws have registering horizontally disposed orifices for receiving a threaded and headed bolt adapted to receive a nut for pulling the jaws toward one another and into intimate contact with the post. When the battery has been used for a considerable time, corrosion frequently so decomposes the parts that the bolt and nut become "frozen" together to such an extent that it is almost impossible to loosen the nut. Also the jaws sometimes become securely attached to the bolt so that it is difficult to spread them even after the nut has been removed.

It is an object of this invention to provide a battery post clamp which avoids the objections to such clamps heretofore known.

Another object of this invention is to provide a battery post clamp which is easy to install and easy to remove.

Another object of this invention is to provide a clamp of the type referred to which automatically locks itself in place upon installation.

Another object of this invention is to provide such a clamp which, when installed, is under constant urge toward tighter contact.

Yet another object of this invention is to provide novel battery post clamp construction, generally.

A still further object of this invention is to provide a novel process for producing a battery post clamp.

In general, my invention in its preferred form, comprises a U-shaped frame having a jaw slidable in opposed guides on the adjacent faces of the legs of the U. A resilient means, for example a spring, urges the said jaw toward the closed end of the U when the device is in operation, the battery post being situated between said closed end and said jaw. A cam mounted on the frame is provided at the rear of the resilient means for at times forcing said resilient means and said jaw toward the battery post. The cam

2

is manually operated by means of a lever and the construction is such that when said lever is moved in the releasing direction its action is positive to withdraw said jaw from the battery post.

5 The battery cable attaches to the aforesaid frame.

In order that a clear and concise understanding of my invention may be had, reference should be made to the accompanying drawing forming 10 a part of this specification in which

Fig. 1 is a top plan view of one embodiment of my invention, covered parts being shown in broken lines.

Fig. 2 is a longitudinal sectional view taken on 15 line 2—2 of Fig. 1.

Referring now more specifically to the drawing, I have used the numeral 10 to designate the generally U-shaped frame or chassis of my clamp. Obviously, of course, the precise shape of the 20 frame 10 is immaterial and it need not consist of a single unit. At the inner face of the closed end 11 of the frame 10, as I have shown it in the drawing, I provide a plurality of relatively sharp protuberances or teeth 12 adapted to 25 tightly grip and even bite into a storage battery post, as will appear more clearly hereafter. Co-operating with the teeth 12 to confine and grip the battery post 13 is the jaw 14 which is longitudinally slidably mounted between the legs 15 and 16 of the frame 10. The operative face of the jaw 14 is preferably knurled as at 17 or otherwise prepared to provide a relatively high friction surface. It is not highly desirable, however, to provide sharp teeth on the jaw 14 inasmuch as 30 retraction or disengagement of the said jaw from the battery post 13 may become undesirably difficult if it have teeth extended deeply into said battery post. Flanges 18 and 19 on the inner face of the leg 15, together with opposed flanges 20 and 35 21, on the inner face of the leg 16 provide a guide for the longitudinal movement of the jaw 14. I have shown the bottom flanges 19 and 21 as of sufficient width to at least substantially meet one another whereby a bottom or closure is provided. Parts 22 and 23 of the flanges 18 and 20 40 respectively, also have been shown to be sufficiently extended that they meet each other to form a closure. While it is not at all essential that the top and bottom of my device be closed so far as practical, it is desirable from both the 45 point of view of appearance and from the point of view of protecting moving parts of the device. To the rear of the jaw 14 and spaced therefrom by the spring or other resilient means 24, is a 50 second member 25 longitudinally slidably re-

ceived in the guide structure on the inner face of the legs 15 and 16. As will become apparent as the disclosure proceeds, the guide structure receiving the plunger member 25 may be separate and distinct from that receiving the jaw 14 rather than being continuous therewith as shown in the drawing. The spring 24 is preferably attached to the jaw 14 at one end and to the plunger 25 at the other. In the drawing I have shown the fastening means to consist of loops 26 and 27 adapted to receive respectively, the end portions 28 and 29 of the wire comprising the coil spring 24. By this construction appreciable movement of the plunger 25 in either direction tends to cause corresponding movement of the jaw 14.

For imparting motion to the plunger 25 a generally vertically extending slot 30 is provided therein adapted to receive an actuating means such as the cam or crankshaft comprising the bent arms or cranks 31 and 32 which are operatively connected to the lever structure designated generally by the numeral 33. Bearings for cranks 31 and 32 are provided in the legs 15 and 16, respectively, at 34 and 35. As is apparent, the drawing illustrates my clamp in post engaging position where it is held by the cranks 31 and 32. Rotation of the lever 33 upwardly causing corresponding rotation of cranks 31 and 32 operates, first, to move the plunger 25 forward slightly due, in part, to the fact that the plunger engaging portions or crankshafts of the cranks 31 and 32 are below their center of rotation when in the relatively stable position shown. Thereafter, continued rotation of the cranks 31 and 32 above their center of rotation causes these cranks to engage the rear wall of the slot 30, whereby the plunger 25, spring 24 and jaw 14 are moved rearwardly to a position out of engagement with the battery post 13. Conversely, rotation of the lever 33 downwardly from a generally upwardly extending position causes the plunger engaging portions of the cranks 31 and 32 to engage the forward wall of the slot 30 forcing the plunger-spring-jaw assembly forward into intimate engagement with the battery post 13. While it is not entirely essential that the cranks 31 and 32 be inclined downwardly relative the lever 33, as they appear clearly in Fig. 2 of the drawing, such construction is preferable for the reason that it provides an automatic lock against accidental disengagement of the jaw 14 from the post 13 since before the crankshaft portions of cranks 31 and 32 can move upwardly and rearwardly, it is necessary, as stated, that they move upwardly and forwardly which movement must be against the very material resistance of the spring 24. Rotation of the cranks downwardly and rearwardly from the position shown in Fig. 2 is, of course, prevented by the flanges 19 and 21 which prevent any downward movement of the plunger 25. In the drawing I have shown a cut-out 36 extending forwardly from the slot 30 adjacent the base thereof. While such cut-out is not at all essential to my invention, especially if other means for locking the jaw 14 in post engaging position be provided, it is a desirable feature for additionally insuring against accidental retraction of the jaw-spring-plunger assembly. As appears clearly in Fig. 2 of the drawing, the crankshaft portions of the cranks 31 and 32 nest in the cut-out portion 36 and the pressure of the spring 24 resists dislodgement of said portions of said cranks from said cut-out, since in order for the said cranks 31 and 32 to disengage the cut-out 36 forward movement of the plunger 25 against the

compression of said spring 24, is required. Obviously when a cut-out such as 36 is provided the distance which the plunger 25 must be moved forwardly by the upwardly rotating cranks 31 and 32 before said cranks can commence rotating upwardly and rearwardly is greater than in the case where the plunger engaging portions of said cranks 31 and 32 are only below their center of rotation when the jaw 14 is in post engaging position. It will be noted from scrutinizing Fig. 2 of the drawing, that the bearings 34 and 35 are shown as located slightly above the center of the depth of the frame 10. This arrangement is not essential, but it is desirable in that it permits greater incline of the cranks 31 and 32 and also permits the lever 33 to be disposed in a substantially horizontal position without being undesirably close to the top of the battery. If desired, protuberances 37 and 38 may be provided on the outer face of the closed end of the frame 10 for further insuring against accidental upward rotation of the lever 33. These protuberances 37 and 38 may be of any suitable nature, but they are preferably rounded or inclined in order to gradually spring the lever structure 33 until it has passed them. Obviously, one or several protuberances may be employed. If desired, the protuberances may be so arranged that some are disposed below the lever 33 when the jaw 14 is in post engaging or forward position. In order to reduce the friction of the plunger engaging portions of the cranks 31 and 32 against the walls of the slot 30, I have provided a tubular member 39 about these portions of said cranks which serves in the nature of a roller bearing. This feature is, of course, optional. Two or more tubes may be employed in place of one.

At the rear of the frame 10, I have shown, for illustrative purposes, a sleeve 40 adapted to receive a battery cable and to be crimped securely thereabout. In order to facilitate the gripping of the cable by said sleeve, I have provided on the inner periphery thereof, rifles 41, whereby said sleeve actually bites into said cable. Arms 42 and 43 are provided on the sleeve 40 for engagement with the rear end portions of the legs 15 and 16 of the frame 10. Any suitable means may be employed in attaching said arms to said legs; care should be taken, however, that a good electrical connection is provided between the two. In the drawing, I have shown fingers or returned flanges 44 on the arms 42 and 43 and 45 on the legs 15 and 16 for engaging, respectively, said legs and said arms whereby the sleeve 40 and the frame 10 are securely united.

In addition to its unique adaptness as battery post clamp for connecting motor vehicle electric cables to wet storage battery posts, my device finds many other applications as a clamp and coupling means. My novel process also may be employed to make devices to be used for other purposes than battery post clamps.

Among the numerous advantages of my novel clamp is the fact that the jaw members always retain their original shape rather than being themselves bent and molded about the battery post; there is thus no chance for failure of the jaws due to their internal breakdown after having been bent back and forth a few times as frequently occurs in the case of the common, presently well-known type of battery post clamp. Since my device provides for an automatic and positive disengagement of the battery post, its removal from the battery present no problem and the necessity for prying and hammering to loosen

it, which operations frequently result in the severe damage or destruction of batteries when standard clamps are being removed, is avoided. By providing engagement of the post by the clamp at only two junctures, I avoid excessive corrosion and all unnecessary confinement of corrosion in contact with the battery post and clamp parts. Again my device may be used with successive cables and/or transferred from one cable to another, for the cable may be simply disengaged from the means connecting it to the clamp. Such is especially easy in the particular connecting means which I have shown in the drawing where spreading of the slit in the sleeve 40 and longitudinal retraction of the cable is all that is required. The action of the resilient means 24 is at least three fold: it provides adaptation means whereby my clamp may be employed on battery posts of various sizes; it provides an engagement with the battery post which is under constant urge toward more intimate contact so that any jar which might tend momentarily to loosen the connection to any extent whatsoever is immediately and positively counteracted by the spring; further the spring operates in connection with the cranks in the slot 30 to maintain the clamp in operative position as heretofore pointed out.

In the claims the term "cam" is intended to include cranks such as 31 and 32 in the drawing, together with standard cams and other devices adapted to at times cause movement in at least one direction. "Jaw" is meant to refer to any device adapted to perform functions similar to those of the parts 11 and 14 of the drawing. "Plunger" as used in the claims does not necessarily require a solid construction or any other precise details sometimes connected with a plunger in its strict sense; any reciprocatable device adapted to perform functions similar, in a general nature, to those of the member 25 is meant to be included.

While specific embodiments of my inventions together with certain modifications thereof have been described in detail for illustrative purposes, it is obvious that one skilled in the art will be able to make variations, eliminations and modifications in the precise structures described and this without departing from the true spirit and scope of my invention. I wish, therefore, to be limited herein only by the appended claims.

I claim:

1. A battery post clamp comprising a frame having one of its portions extending generally right angular to another one of its portions, the latter portion engaging one side of a battery post when in operative position, a battery post engaging jaw slideable along the first of said frame portions toward and away from second said frame portion for engaging the opposite side of said battery post from that engaged by second said frame portion, a plunger also slideable along first said frame portion having in its side wall structure an elongated cut-out disposed generally normal to the plane of said frame, a resilient connection connecting said jaw to said plunger, a crank having its crank shaft received in said cut-out for imparting motion to said plunger and having its crank pin journaled in first said frame portion, and a lever connected to said crank.

2. A battery post clamp comprising a frame having one of its portions extending generally right angular to another one of its portions, the latter portion engaging one side of a battery

post when in operative position, a battery post engaging jaw slideable along the first of said frame portions toward and away from second said frame portion for engaging the opposite side of said battery post from that engaged by second said frame portion, a plunger also slideable along first said frame portion having in its sidewall structure an elongated cut-out disposed in the direction of the depth of said plunger, which is also the direction of the depth of said frame, said cut-out being enlarged at its base end in the direction of the forward end of said plunger and the top of said enlarged portion being inclined downwardly and forwardly from the forward wall of the unenlarged portion of said cut-out, a resilient connection connecting said jaw to said plunger, a crank having its crank pin journaled in first said frame portion and having its crank shaft received in said cut-out, the arrangement being such that the point at which said crank pin is journaled in said frame member is more adjacent the unenlarged end of said cut-out, considering the depth direction only, than is the enlarged end of said cut-out, and a lever connected to said crank.

3. A battery post clamp comprising a frame having generally parallel members and a portion connecting said parallel members said latter portion engaging one side of a battery post when in operative position, guide structure on the adjacent faces of said parallel members, a jaw slidably received in said guide structure and engaging the opposite side of said battery post when in operative position, a plunger also slidably received in said guide structure, having in its side wall structure an elongated cut-out disposed in the direction of the depth of said plunger, which is also the direction of the depth of said frame, said cut-out being enlarged at its base end in the direction of the forward end of said plunger, and the top of said enlarged portion being inclined downwardly and forwardly from the forward wall of the unenlarged portion of said cut-out, a resilient connection connecting said jaw to said plunger, a crank having its crank pin journaled in one of said parallel frame members and having its crank shaft received in said cut-out, the arrangement being such that the point at which said crank pin is journaled in said frame member is more adjacent the unenlarged end of said cut-out, considering the depth direction only, than is the enlarged end of said cut-out, and a lever connected to said crank.

4. A battery post clamp comprising a frame having generally parallel members and a portion connecting said parallel members, said latter portion engaging one side of a battery post when in operative position, a jaw longitudinally slidably mounted between said parallel members and engaging the opposite side of said battery post when in operative position, a plunger also longitudinally slidably mounted between said parallel members having in its sidewall structure an elongated cut out disposed in the direction of the depth of said plunger, which is also the direction of the depth of said frame, said cut-out being enlarged at its base end in the direction of the forward end of said plunger, and the top of said enlarged portion being inclined downwardly and forwardly from the forward wall of the unenlarged portion of said cut-out, a resilient connection connecting said jaw to said plunger, a crank having its crank pin journaled in one of said parallel frame members and having its crank shaft received in said cut-out, the arrangement

being such that the point at which said crank pin is journaled in said frame member is more adjacent the unenlarged end of said cut-out, considering the depth direction only, than is the enlarged end of said cut-out, and a lever connected to said crank.

5. A battery post clamp comprising a frame having generally parallel members and a portion connecting said parallel members, said latter portion engaging one side of a battery post when in operative position, a battery post engaging jaw slidably mounted between said parallel members for engaging the opposite side of said battery post, a crank journaled on one of said parallel members in a position such that its crank shaft is spaced from said jaw and is disposed to that end of said jaw which is opposite to that end thereof which engages said battery post, and means including a coil spring connecting said jaw to said crank shaft whereby partial rotation of said crank in one direction causes said jaw to engage said battery post and partial rotation of said crank in the opposite direction causes it to disengage said battery post.

6. A battery post clamp comprising a frame having generally parallel members and a portion connecting said parallel members said latter portion engaging one side of a battery post when in operative position, a battery post engaging jaw longitudinally slidably mounted between said parallel members for engaging the opposite side of said battery post, a plunger also longitudinally slidably mounted between said parallel members spaced from said jaw and located in alignment therewith to that end thereof which is opposite to its battery post engaging end, said plunger having an elongated cut-out in its side wall structure disposed in the direction of the depth of said plunger, which is also the direction of the depth of said frame, a crank journaled on one of said parallel frame members and having its crank shaft projecting into said cut-out for reciprocating said plunger, a lever connected to said crank for rotating the same and a coil spring positively connecting said jaw to said plunger whereby reciprocation of the latter results in the engagement and disengagement of said battery post by said jaw.

7. For a battery post clamp the combination comprising an elongated frame section, structure

connected to said frame section and engaging one side of a battery post when in operative position, a member disposed to the opposite side of said battery post when in operative position and reciprocatable along said frame section, said reciprocatable member having in its side wall structure an elongated cut-out disposed in the direction of the depth of said reciprocatable member, which is also the direction of the depth of said frame section and said post engaging structure, said cut-out being enlarged at its base end in the direction of the forward end of said reciprocatable member and the top of said enlarged portion being inclined downwardly and forwardly from the forward wall of the unenlarged portion of said cut-out, a crank having its crank pin journaled on said frame section and having its crank shaft received in said cut-out, the arrangement being such that the point at which said crank pin is journaled in said frame section is more adjacent the unenlarged end of said cut-out, considering the depth direction only, than is the enlarged end of said cut-out, and a lever connected to said crank.
